UNITED STATES PATENT OFFICE

164,693

SLICING DEVICE

Clarence R. Koons, Secaucus, N. J.

Application July 26, 1949, Serial No. 4,141

Term of patent 7 years

(Cl. D89—1)

To all whom it may concern:

Be it known that I, Clarence R. Koons, a citizen of the United States of America, residing at Secaucus, in the county of Hudson, State of New Jersey, have invented a new, original, and ornamental Design for a Slicing Device, of which the following is a specification, reference being had to the accompanying drawings forming a part thereof, in which:

Fig. 1 is a perspective view of a slicing device, showing my new design.

Fig. 2 is a front view.

Fig. 3 is an end view.

I claim:

The ornamental design for a slicing device, as shown.

CLARENCE R. KOONS.
